JOHN C. FOGARTY INVENTOR.

BY C. F. Bond

his ATTORNEY.

UNITED STATES PATENT OFFICE.

JOHN C. FOGARTY, OF GREEN BAY, WISCONSIN, ASSIGNOR TO NORTHERN PAPER MILLS, OF GREEN BAY, WISCONSIN, A CORPORATION OF WISCONSIN.

PAPER-TOWEL CONTAINER.

1,188,166.

Specification of Letters Patent. Patented June 20, 1916.

Application filed December 4, 1915. Serial No. 65,047.

To all whom it may concern:

Be it known that I, JOHN C. FOGARTY, a citizen of the United States of America, residing at Green Bay, in the county of Brown and State of Wisconsin, have invented certain new and useful Improvements in Paper-Towel Containers, of which the following is a specification, reference being had therein to the accompanying drawing.

10 The invention relates to containers for paper towels and the like, wherein towels are interfolded in such a manner that one end of the lowermost towel extends through a slot in the bottom of the container and 15 the withdrawal of the lowermost towel causes the end of the next towel to project through the same slot.

The principal object of the invention consists in the provision of means whereby the 20 friction due to the withdrawal of the towels may be greatly reduced.

Another object of the invention consists in the provision of a container whose slot 25 can be automatically widened when its door is opened so that the end of the lowermost sheet may be conveniently passed through the slot.

With these and other objects in view, the invention consists in a novel combination 30 and arrangement of parts to be hereinafter described and specifically pointed out in the appended claims.

In the accompanying drawings Figure 1 is a transverse view of the container showing a stack of towels interfolded therein. Fig. 2 is a transverse view of the container with the door section opened and a tilting bottom in position for loading. Fig. 3 is a 35 perspective view of the container.

With reference to the drawings, 1 denotes a suitable container, substantially of rectangular form, provided with a door 2-hingedly connected thereto. The container 1 is provided with a bottom plate 3 which may 40 be integral with or connected to the back wall of the container. The bottom plate 3 is provided with a raised portion 4 and a downwardly curved flange 5. Spaced from the plate 3 a bottom plate 6 is tiltably 45 mounted on a pin 12 secured to opposite side walls of the container. The pivot pin 12 is so arranged with respect to the plate 6 that the weight of the same will tilt the inner edge of the plate downwardly. From 50 the foregoing it is obvious that when the

bottom plate 6 is tilted the opening 9 between the inner edges of the plates will be widened so as to make it more convenient to insert the edge of a sheet of a new stack introduced into the container. The bottom 60 plate 6 similar at its coöperating plate 3 is provided with a raised portion 7 and a downwardly curved flange 8 at its inner end. The other side of the plate is provided with a flange 10 adapted to be engaged by the door 2 when the same is in the closing position. From the foregoing it is obvious that when the door is in open position the bottom plate 6 will assume the position indicated in Fig. 2. Upon the introduction of 65 a stack of towels the plate 6 is brought nearly into its operative position and is locked therein when the door section 2 is in closing position, whereupon the plate 6 assumes the position shown in Fig. 1. In the 70 side walls of the container slots 11 are provided whereby the amount of towels contained in the box may be readily observed.

It has been found that when a sheet of paper is withdrawn from the container the greatest friction occurs at the initial movement of the sheet, since the edge 14 thereof must turn so as to be drawn to the opening 9. To this end the raised portions 4 and 7 are provided whereby the towels are prevented from engaging the bottom plates and a space is defined wherein the edge 14 may turn without contacting with the bottom. After the sheet has been curled no difficulty is experienced in carrying it over the 80 raised portions.

I am aware that various changes in the construction of the container may be made, without departing from the spirit of the invention, and I do not restrict myself to the specific form shown in the drawings, but want to avail myself of all such departures which come within the scope of the appended claims.

I claim:

1. A container having wall sections, a door section hingedly attached thereto and a bottom section made up of a pair of spaced plates, one of said plates being connected to said wall sections, the other of said bottom plates being pivotally mounted between its appertaining wall sections and adapted to be locked in operative position by said door section when the same is in closing position.

110

2. A container having wall sections, a door section hingedly attached thereto and a bottom section made up of a pair of spaced plates, one of said plates being connected to said wall sections, the other of said bottom plates being mounted to oscillate about a longitudinal axis between its appertaining wall sections and adapted to be engaged by said door section when in closing position, so as to be locked in operative position. 10
3. A container having wall sections, a door section hingedly attached thereto and a bottom section made up of a pair of plates, one of said plates being connected to said wall sections, the other of said plates being spaced from said first mentioned plate and pivotally mounted between its appertaining wall sections about a longitudinal axis adjacent its other edge, said door cooperating with said movable plate for locking the same in operative position. 15
4. A container having wall sections, a stationary and a tilttable bottom plate, said tilttable plate being spaced from said stationary plate and being provided with a flange at right angles thereto, and a door engaging said flange for locking said tilttable plate in operative position. 20
5. A container for paper towels and the like, having wall sections, a door hingedly connected thereto and a bottom section made up of a pair of spaced plates, one of said plates being connected to said wall section, the other of said bottom plates being tiltably mounted between its appertaining wall sections and adapted to be locked in operative position by said door section when the same is in closing position, and means for decreasing the friction upon the withdrawal of the towels. 25
6. A container for paper towels and the like, having wall sections, a stationary and a tilttable bottom plate spaced from said stationary plate, means for locking the movable plate in operative position and means for decreasing the friction upon the withdrawal of the towels. 30
7. A container for paper towels and the like, having wall sections, a stationary and a tilttable bottom plate, said tilttable plate being spaced from the said stationary plate and being provided with a flange at right angles thereto, and a door engaging said flange for locking said tilttable plate in operative position, said bottom plates being provided with raised portions for preventing engagement of the towels with the bottom plates, whereby the friction upon the withdrawal of the towels is reduced. 35

In testimony whereof I hereunto affix my signature.

JOHN C. FOGARTY.
